C. R. Wright Jr.

Attorney

UNITED STATES PATENT OFFICE.

EDWARD L. DELANY, OF BROOKLYN, NEW YORK.

BRACKET FOR FLUSH TANKS.

Application filed March 17, 1922. Serial No. 544,601.

To all whom it may concern.

Be it known that I, EDWARD L. DELANY, of Brooklyn, in the county of Kings and State of New York have invented certain new and useful Improvements in Brackets for Flush Tanks; and I do hereby declare the following to be a full, clear, and exact description of the invention, such as will enable others skilled in the art to which it appertains to make and use the same.

My invention relates to improvements in float valve supporting brackets for flush tanks.

The object of my invention is to provide a bracket of this character which is supported by the upper edge of the overhead flush tank and which is so constructed that the float valve can be arranged at either end of the tank, and the flush valve operating lever supported thereby so that it is at all times arranged in the same alinement relative to the sides of the tank when the float valve is arranged at either end of the tank.

Another object of my invention is to provide a bracket of this character in which the float valve can be so attached thereto that the supply connection thereof can extend upwardly along the side of the tank, or can be so attached that an overhead water supply connection can be made in which the supply pipe is wholly within a vertical line of the flush tank so that the water supply is hidden from view.

A further object of my invention is to provide a simple, cheap and effective bracket of this character having certain details of structure and combination of parts hereinafter more fully set forth.

In the accompanying drawings:

Figure 1 is a perspective view of my improved bracket.

Figure 2 is a top plan view showing the float valve in dotted lines and showing the water supply extending upwardly along the side of the tank.

Figure 3 is a similar view showing the float valve with the water supply extending from above, and in which event the water supply is hidden from view.

Figure 4 is a top plan view of a flush tank showing a bracket secured at each end of the tank and showing the two different positions of the float valve on the bracket.

The invention is more particularly in-

tended for composition flush tanks wherein, in the manufacture thereof it is necessary to provide attaching means for the bracket and which allows for the adjustment of the float valve to provide for a water connection from below or above, or to allow for either connection at either end of the tank, and at the same time providing means whereby the flush valve lever can be arranged to extend over either end of the tank.

Referring now to the drawings, 1 represents the tank and has adjacent each end a reinforcing metal strip 2, at the top of the rear wall. I have shown one of these metal strips 2 arranged adjacent each end of the tank. This reinforcing strip is provided with the shoulder 3 which indicates the proper position of the bracket on the tank, and said strips are provided with screw holes for receiving the screws 5 for holding the bracket 4 to the upper edge of the tank. This bracket 4 as shown in the drawings comprises a flat metal plate 80 adapted to rest upon the strip 2 and secured thereto by means of screws 5 passing through the screw openings 5'. The opposite edge of the bracket is provided with a cleft 6 to receive the projection or headed member 6', carried by the front wall of the flush tank. From this structure it will be seen that the bracket necessarily has to be secured to the tank at either end at a predetermined point so that when in position at either end of the tank the flush valve operating lever assumes the proper position to properly operate the valve. By this structure, the bracket is rigidly held on the tank against vertical or lateral movement. 95 The upper face of the bracket 4 is provided with ears 7 in which the flush valve operating lever 8 is fulcrumed, all of which is well understood and needs no further description. The bracket 4 is provided in one edge with a shallow recess 9 and the deep recess 10 and in the other edge with the shallow recess 11 and the deep recess 12 arranged directly opposite the recesses 9 and 10. The inner faces of the deep recesses 10 and 12 are in horizontal alinement as shown in Figure 3 of the drawings. The bracket 4 is provided with the T-shaped slot 13 on one side of the recess 9 and the elongated transverse slot 14 on the opposite side of the recess. The bracket 4 is provided on one side of the recess 11 with

the T-shaped slot 15 and on the opposite side with an elongated transverse slot 16. By this construction and the construction of the float valve the same can be secured 5 in position with the discharge pipe thereof in any of the four recesses 9, 10, 11 and 12. The float valve, as indicated at 17 is provided on opposite sides with ears 18 and 19 having openings therein through which 10 bolts 20 pass, and by means of which the float valve is secured to the bracket by the bolts passing through the slots 13, 14, 15 and 16 as will be hereinafter more fully described. The float valve 17 is provided 15 with a water supply pipe 21 and when the float valve is arranged with the discharge pipe 22 in the recess 10 the bolts 20 pass through the slots 15 and 16 and firmly hold the flush valve to the bracket. When it is 20 desired to make an over head connection, the flush valve 17 is moved rearwardly on the bracket with the discharge pipe 22 within the recess 9 which brings the inlet supply pipe in beyond the end of the tank and 25 wholly hides the same, when it is desired to bring the water supply from above. This adjustment, it will be seen, does not interfere at all with the flush valve operating lever and thus the adjustment can be made, 30 and the mechanic can be assured that the flush valve operating lever is in its proper position. When it is desired to put the water supply and flush valve operating lever at the opposite end of the tank, the bracket 35 is moved in the position shown in Figure 4 of the drawings. In this view I have shown the two complete brackets and flush valves showing them in dotted and full lines to fully illustrate the four portions 40 that the float valve can be arranged on the tank by the single bracket.

Having thus described my invention, what I claim is:

1. An interchangeable bracket for flush tanks, adapted for attachment to the upper edge of the tank adjacent either end and adapted to support a float valve, and a flush valve operating lever.
2. An interchangeable bracket for flush tanks, adapted to be attached to the upper end of the tank adjacent either end and adapted to support a float valve with the water supply on the outside of the tank

or wholly above the tank, and having means for pivotally supporting the flush valve operating lever and so constructed that the operating lever will operate when the bracket is attached adjacent either end of the tank.

3. An interchangeable bracket for flush tanks, adapted to be attached to the upper edge of the tank adjacent either end and adapted to adjustably support a float valve so that the water supply may extend from below on the outside of the tank or wholly above the tank, and having means for pivotally supporting the flush valve operating lever and so constructed that it can be attached adjacent either end of the tank with the several parts in their proper positions.

4. An interchangeable bracket for flush tanks, adapted to be attached to the upper edge of the tank adjacent either end and comprising a plate having means for pivotally supporting the flush valve operating lever, and having a series of openings for securing the float valve thereto in different positions.

5. An interchangeable bracket for flush tanks, adapted to be attached to the upper edge of the tank adjacent either end and comprising a plate having means for pivotally supporting the operating lever of the flush valve, and having in its edges a series of relatively deep and shallow recesses, and said plate having a series of slots whereby the float valve may be secured thereto in different positions.

6. An interchangeable bracket for flush tanks, adapted to be attached to the upper edge of the tank adjacent either end and comprising a plate having means adapted to pivotally support the operating lever of the flush valve, and having in each of its side edges a relatively deep recess and a relatively shallow recess oppositely arranged, and a series of slots arranged with bolts for clamping a float valve to the plate adjacent the deep recess on one side or the shallow recess on the other side when at one end of the tank and in the opposite positions when the bracket is arranged at the opposite end of the tank.

In testimony whereof I have signed this specification.

EDWARD L. DELANY.
